US00D796964S

(12) **United States Design Patent** (10) **Patent No.:** **US D796,964 S**
Staab (45) **Date of Patent:** **** Sep. 12, 2017**

(54) **COSMETIC BOTTLE**(71) Applicant: **Mary Kay Inc.**, Addison, TX (US)(72) Inventor: **Jenny DeMarco Staab**, Frisco, TX (US)(73) Assignee: **Mary Kay Inc.**, Addison, TX (US)(**) Term: **15 Years**(21) Appl. No.: **29/586,213**(22) Filed: **Dec. 1, 2016****Related U.S. Application Data**

(62) Division of application No. 29/537,488, filed on Aug. 26, 2015, now Pat. No. Des. 776,544.

(51) **LOC (10) Cl.** **09-01**(52) **U.S. Cl.**USPC ..... **D9/560**; D9/574; D9/520(58) **Field of Classification Search**

Primary Examiner — Thomas Johannes*Assistant Examiner* — Keith Frank(74) *Attorney, Agent, or Firm* — Norton Rose Fulbright US LLP(57) **CLAIM**

The ornamental design for a cosmetic bottle, as shown and described.

DESCRIPTION

FIG. 1 is a top perspective view of a cosmetic bottle showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate the portions of the cosmetic bottle that form no part of the claimed design.

1 Claim, 6 Drawing Sheets# US D796,964 S
